UNITED STATES PATENT OFFICE.

PATRICK BRADY, OF CAMBRIDGEPORT, MASSACHUSETTS.

MANUFACTURE OF LAMP-SHADES.

SPECIFICATION forming part of Letters Patent No. 352,641, dated November 16, 1886.

Application filed February 17, 1886. Serial No. 192,203. (No model.)

To all whom it may concern:

Be it known that I, PATRICK BRADY, of Cambridgeport, in the county of Middlesex, of the Commonwealth of Massachusetts, have invented a new and useful Improvement in the Manufacture of Lamp Shades; and I do hereby declare the same to be described in the following specification and represented in the accompanying drawings, of which—

10 Figure 1 is a top view, Fig. 2 a side elevation, and Fig. 3 a transverse and central section, of a lamp-shade in accordance with my invention, the nature of which is defined in the claim hereinafter presented.

15 The said shade is made of glass "silvered" on its inner surface or surfaces. It is concavo-convex, and at its crown has two necks concentric with each other, one being within the other, and the two having an annular space 20 between them and opening into that between the dome-shaped parts of the shade.

The said shade in other respects is composed of two dome-shaped sections united together at their bases, one of which sections extends up 25 within and concentrically with the other, with a narrow space between the two, each at its crown having a cylindrical tubular neck extending upward from it, as represented.

In the drawings, A and B are the dome-shaped sections; C and D, their tubular necks; E, the space between such necks, and F that 30 between the two sections.

After the article or lamp-shade has been made of glass it is to have silver in a thin 35 layer deposited over its entire inner surface, which may be effected by a process well known in the arts. Usually the shade is finished by a suitable metallic annular cap, G, covering the upper ends of the two necks.

This shade is for use with a lamp whose 40 glass chimney is to extend upward through the inner neck of the shade.

I am aware that a glass reflector has been made hollow and with a single neck or mouth, such reflector being silvered on its inner sur- 45 face, and therefore I do not claim such.

In making the shade it is first blown in the form of a hollow segment of a sphere with a single neck—viz., the outer one—at its crown, after which I heat the flat or base part of the 50 segment and draw or force it within the arcal part making it dome-shaped. Next I heat it again at its central part, and by means of a cylindrical plug force each part within the said neck, so as to force within it the inner 55 neck, after which I cut off both necks evenly to the length required. In this case I make no claim for the article.

I claim—

The process, substantially as described, of 60 making the aforesaid lamp-shade, it consisting in first blowing it in the form of the hollow segment of a sphere with a single neck projecting from its crown, next heating the base part and pressing or drawing it within the 65 arcal part, so as to form the inner dome therein, next heating this latter at its central part and forcing it inward into the said neck, so as to form the said inner dome with a neck 70 projecting within that of the outer dome, all being essentially as specified.

PATRICK BRADY.
